UNITED STATES PATENT OFFICE.

AARON JEDEL, OF NEW YORK, N. Y.

PYROTECHNICAL TOY.

No. 888,810.

Specification of Letters Patent.

Patented May 26, 1908.

Application filed November 20, 1907. Serial No. 402,965.

To all whom it may concern:

Be it known that I, AARON JEDEL, citizen of the United States, residing at New York, in the county of New York and State of New York, have invented certain new and useful Improvements in Pyrotechnical Toys; and I do hereby declare the following to be a full, clear, and exact description of the invention, such as will enable others skilled in the art to 10 which it appertains to make and use the same, reference being had to the accompanying drawings, and to figures of reference marked thereon, which form a part of this specification.

This invention has reference, generally, to improvements in pyrotechnical toys; and the invention relates, more particularly, to a novel form of pyrotechnical toy, which is known in the art as an electric sparkler, and 20 the same consists, generally, in the application of a suitable pyrotechnical composition, for fire-works and other pyrotechnical devices, to a portion of a suitable wire or other support, which is rotatably connected to a 25 stem or handle, so that, when the pyrotechnical composition is ignited, the device can be swung or rotated about the stem, and thereby produce beautiful pin-wheel effects.

My present invention has for its principal 30 objects to provide a novel and simple pyrotechnical toy of the general character herein-after more particularly set forth and which can be readily manipulated and safely handled during the ignition of the pyrotechnical 35 composition.

Other objects of this invention not at this time more particularly mentioned will be clearly evident from the following detailed description of the same.

The invention is clearly illustrated in the accompanying drawings, in which:—

Figure 1 is a face view of the pyrotechnical toy, illustrating one embodiment of my present invention; Fig. 2 is a similar view of 45 the pyrotechnical toy, certain portions of the device, however, being represented in vertical section; and Fig. 3 is a transverse section of the said device, said section being taken on line 3—3 looking in the direction of arrow x. Fig. 4 is a view similar to that shown in Fig. 2 of a slightly modified construction 50 of the pyrotechnical toy.

Similar characters of reference are employed in all of the above described views, to 55 indicate corresponding parts.

Referring now to the said drawings, the reference-character 1 indicates the complete pyrotechnical toy embodying the principles of the present invention, and the same comprises a suitable rod 2 of wire, or flat band-metal, which is preferably spirally twisted, substantially in the manner shown in the several figures of the drawings. This rod or bar 2 carries upon a portion thereof a pyrotechnical compound or mixture 3, and upon its upper end-portion the said rod or bar 2 is made with suitable means of suspension 4, such as a loop or eye, or other means, which will serve the same purpose. The said loop or eye is loosely arranged over a suitably 70 formed stem 5, upon which are mounted, one upon each side of said loop or eye, suitable beads, as 6, which form annular shoulders or stops to prevent any undue lateral movement and displacement of said loop or eye 75 from the said stem 5, but will not interfere with the rotary or swinging movement of the rod 2 and its pyrotechnical compound about the stem 5, as will be clearly evident.

Instead of making the beads 6 separate 80 from the stem 5, and securing them upon said stem by frictional holding engagement, a stem 7 which is provided with annular enlargements 8 forming an integral part of the stem 7, and between which the loop or eye, 85 or other means of suspension of the bar or rod 2 is disposed in the manner previously described, may be used, as clearly illustrated in Fig. 4 of the drawings.

The manner of using the device, after the 90 pyrotechnical compound has been ignited, will be clearly understood from an inspection of the several figures of the drawings; and, it will be evident, that I have devised a simple, neat and effective pyrotechnical toy, 95 which can be easily manipulated to produce a rotary or swinging movement of the suspended pyrotechnical compound or body, without any danger of burning oneself.

Of course I am aware that changes may be 10 made in the general arrangements and combinations of the parts, as well as in the details of the construction of the same, without departing from the scope of this invention as defined in the claims which are appended to 10 this specification. Hence I do not limit my invention to the exact arrangements and combinations of the parts as described in the foregoing specification and as illustrated in the accompanying drawings, nor do I con- 11

fine myself to the exact details of the construction of any of the said parts.

I claim:

1. A pyrotechnical toy comprising a rod, said rod being made with a spiral twist, a pyrotechnical compound secured upon a portion of said spiral twist, said rod having a means of rotary suspension, combined with a stem which serves as a handle, and from which said rod is suspended so as to be capable of receiving a swinging motion, substantially as and for the purposes set forth.

2. A pyrotechnical toy comprising a rod provided upon a portion thereof with a pyrotechnical compound, said rod having a means of rotary suspension, combined with a stem which serves as a handle, and from which said rod is suspended so as to be capable of receiving a swinging motion, and a pair of annular beads upon said stem, said beads being formed with rounded surfaces and being located on opposite sides of the means of suspension to prevent lateral movement and displacement of the rod from said stem, substantially as and for the purposes set forth.

3. A pyrotechnical toy comprising a rod provided upon a portion thereof with a pyrotechnical compound, said rod having a means of rotary suspension, combined with a stem which serves as a handle, and from which said rod is suspended so as to be capable of receiving a swinging motion, and a pair of beads mounted upon said stem and held thereon by frictional contact, said beads being located on opposite sides of the means of suspension to prevent lateral movement and displacement of the rod from said stem, substantially as and for the purposes set forth.

4. A pyrotechnical toy comprising a rod, said rod being made with a spiral twist, a pyrotechnical compound secured upon a portion of said spiral twist, said rod being provided at its upper end with a loop which

serves as a means of rotary suspension, combined with a stem which serves as a handle, and from which said rod is suspended so as to be capable of receiving a swinging motion, and means on said stem to prevent lateral movement and displacement of the rod from said stem, substantially as and for the purposes set forth.

5. A pyrotechnical toy comprising a rod provided upon a portion thereof with a pyrotechnical compound, said rod being provided at its upper end with a loop which serves as a means of rotary suspension, combined with a stem which serves as a handle, and from which said rod is suspended so as to be capable of receiving a swing motion, and a pair of beads upon said stem, said beads being formed with rounded surfaces and being located on opposite sides of the loop of said rod to prevent lateral movement and displacement of the rod from said stem, substantially as and for the purposes set forth.

6. A pyrotechnical toy comprising a rod provided upon a portion thereof with a pyrotechnical compound, said rod being provided at its upper end with a loop which serves as a means of rotary suspension, combined with a stem which serves as a handle, and from which said rod is suspended so as to be capable of receiving a swing motion, and a pair of beads mounted upon said stem and held thereon by frictional contact, said beads being located on opposite sides of the loop of said rod to prevent lateral movement and displacement of the rod from said stem, substantially as and for the purposes set forth.

In testimony that I claim the invention set forth above I have hereunto set my hands this 18th day of November, 1907.

AARON JEDEL.
